US00D799698S

(12) **United States Design Patent** (10) **Patent No.:** **US D799,698 S**
Radau et al. (45) **Date of Patent:** **** Oct. 10, 2017**

(54) **PART OF PROSTHESIS**

(71) Applicant: **OTTO BOCK HEALTHCARE PRODUCTS GMBH**, Vienna (AT)

(72) Inventors: **Nils Eduard Radau**, Salzburg (AT); **Stephan Lintner**, Elsbethen (AT); **Carlos Ramos Alzamora**, Salzburg (AT); **Anna Neumann**, Elsbethen (AT)

(73) Assignee: **OTTO BOCK HEALTHCARE PRODUCTS GMBH**, Vienna (AT)

(**) Term: **15 Years**

(21) Appl. No.: **35/500,382**

(22) Filed: **Oct. 23, 2015**

(80) **Hague Agreement Data**

Int. Filing Date: **Oct. 23, 2015**

Int. Reg. No.: **DM/088536**

Int. Reg. Date: **Oct. 23, 2015**

Int. Reg. Pub. Date: **Dec. 18, 2015**

(30) **Foreign Application Priority Data**

Apr. 24, 2015 (EM) 002689075

(51) **LOC (10) Cl.** **24-03**

(52) **U.S. Cl.**

USPC **D24/155**

(58) **Field of Classification Search**

USPC D24/155, 171; 623/29, 33, 27, 37, 39; 264/219, 511

CPC .. A61F 2/5046; A61F 2/60; A61F 2/78; A61F 2/64

(57) **CLAIM**

The ornamental design for a part of prosthesis, as shown and described.

DESCRIPTION

1. Part of prosthesis

FIG. 1.1 is a front perspective view;

FIG. 1.2 is a rear perspective view;

FIG. 1.3 is a rear view;

FIG. 1.4 is side view;

FIG. 1.5 is a front view;

FIG. 1.6 is top view; and

FIG. 1.7 is bottom view.

In the drawings, the broken lines are for the purpose of illustrating environment only and form no part of the claimed design.

1 Claim, 6 Drawing Sheets
